THICKNESS PLANER JOINTER
ATTACHMENT

Walter Ramm, Tulsa, Okla.

Application February 2, 1951, Serial No. 209,135

13 Claims. (Cl. 144—117)

1

The invention relates to jointer attachments and particularly to an attachment whereby the jointer can be utilized as a thickness planer by a simple device, easily and quickly attached to the jointer fence, thereby allowing the utilization of a conventional form of jointer as a thickness planer without the expense of having a separate machine.

A further object is to provide a jointer attachment supported by the jointer fence, so that said jointer can be utilized as a thickness planer when desired. The device is particularly adapted for home workshops where the limited use of a thickness planer would prohibit the purchase of a separate machine.

A further object is to provide a thickness planer attachment for a jointer comprising a plate detachably connected to the face of the jointer fence and provided with a vertically adjustable member for engagement with the upper side of a piece of material being passed through the jointer for the planing operation, and spring means for normally forcing the material upwardly for close engagement with the adjusted limiting device.

A further object is to provide scale means whereby the material may be cut to a predetermined dimension.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a perspective view of the front side of the attachment.

Figure 2 is a perspective view of the rear side of the attachment.

Figure 3 is a front elevation of a conventional form of jointer showing the device applied thereto.

Figure 4 is a top plan view of the jointer showing the device applied thereto.

Figure 5 is a side elevation of the jointer showing the attachment in side elevation.

Referring to the drawings, the numeral 1 designates a jointer stand and 2 the jointer frame. The jointer frame 2 is provided with the rear stationary bed plate 3 and the forward bed plate 4, which bed plate 4 is adjustable upwardly and downwardly in relation to the bed plate 3. Rotatably mounted between the adjacent ends of the bed plates 3 and 4 is a cutter head 5 having

2

a cutter knife 6. Disposed to one side of the bed plates is a conventional form of fence 7, which may be angularly adjusted, however it is shown in the drawing as at 90 degrees from the plane of the bed plates. The above structure is conventional.

The thickness planer attachment comprises a plate 8, which plate is attached to the fence 7 by hand screws 9 of the shouldered type which extend through the fence and thread into the apertures 10 of the plate 8. Plate 8 forms an upward extension extending above the fence and supporting means for supporting the angularly shaped material engaging member 11. The member 11 comprises a vertical flange 12 which is in face engagement with the supporting plate 8 and the horizontal flange 13 which engages the upper side of material being passed through the device. The rear side of the flange 12 is provided with an elongated lug 14, which lug 14 slides in a vertical slot 15 extending through the supporting plate 8, and the lug 14 and the angular member 11 are locked in vertically adjusted positions by a lock screw 16, which screw threads into the lug 14, and is provided with a flange 17 for jamming against the rear side of the supporting plate 8, see Figure 3. It will be seen that the member 11 can be adjusted to various elevations in relation to the bed plates 3 and 4 and the cutting element, and can be securely clamped in its adjusted position.

Pivotedly connected at 18 to the upper side of the supporting plate 8 is an arm 19, extending over the member 11 and connected to the flange 13 by a link 20, therefore the operator can adjust the device upwardly or downwardly to the proper elevation according to the scale 21 carried by the flange 12 and the stationary pointer 22 carried by the supporting plate 8.

In applying the device to the fence, the bed plate 4 is adjusted downwardly as shown in Figure 5, preferably one half inch, and it will be seen that the lower edge of the supporting plate 8 has one portion thereof downwardly offset as shown in Figures 2 and 5 to rest on both bed plates. Secured by means of a bolt 23 to the upper side of the adjustable bed plate 4 is a multiple fingered pressure member 24, the ends of the fingers of which are bent downwardly at ninety degrees as shown at 25. The other edge of the member 24 is provided with a lug 26 received in the notch 27 in the lower edge of the supporting plate 8, hence it will be seen that the member 24 can not pivotally move, and these parts, as well as all of the attachments

can be easily and quickly applied to the jointer or removed, according to the type of work being done.

In operation, material is fed through the device, referring to Figure 5, from right to left. The material is forced upwardly against the flange 13 by the upward spring action of the member 24 and its various fingers, hence the material is in close contact with the under side of the previously set flange 13 at the time it reaches the cutters 6 for planing the lower side of the material to a predetermined thickness, as it continues to the left through the machine. It will be seen that successive pieces of material can be accurately planed to a predetermined dimension. It will also be seen that by simply loosening the locking screw 16 the operator can easily and quickly adjust the device for planing to a different size.

From the above it will be seen that a thickness planer attachment is provided which may be easily and quickly attached to a conventional form of jointer fence and jointer without modifying the construction of the fence or jointer.

The invention having been set forth what is claimed as new and useful is:

1. The combination with a jointer, said jointer having a stationary bed plate and an upwardly and downwardly adjustable bed plate adjustable into and out of the plane of the stationary bed plate, a rotatable cutter between said bed plates, a fence extending upwardly from the sides of the bed plates, of a thickness gauge carried by said fence, means for adjusting said gauge upwardly and downwardly in relation to the bed plates, said thickness gauge comprising a supporting plate secured to the inner side of the fence, a thickness gauge vertically adjustable on the supporting plate and material engaging spring means carried by the adjustable bed plate and adapted to engage the under side of material passing through to maintain the upper side of the material in close engagement with the under side of the thickness gauge.

2. The combination with a jointer, said jointer having a stationary bed plate and an upwardly and downwardly adjustable bed plate adjustable into and out of the plane of the stationary bed plate, a rotatable cutter between said bed plates, a fence extending upwardly from the sides of the bed plates, of a thickness gauge carried by said fence, means for adjusting said gauge upwardly and downwardly in relation to the bed plates, said thickness gauge comprising a plate

secured to the inner side of the fence and extending upwardly above the fence, a horizontal gauge member carried by the plate, said horizontal gauge member having a slidable connection with the supporting plate, lever means for raising and lowering said horizontal gauge member, cooperating scale and pointer members carried by the supporting plate and the gauge member, upwardly inclined spring fingers carried by the movable bed plate and extending inwardly towards the cutter, said spring fingers forming means for engaging the under side of material passing through the device and maintaining the upper side of the material passing through the device in sliding engagement with the under side of the gauge member.

3. The combination with a jointer, said jointer having a stationary bed plate and an upwardly and downwardly adjustable bed plate adjustable into and out of the plane of the stationary bed plate, a rotatable cutter between said bed plates, a fence extending upwardly from the sides of the bed plates, of a thickness gauge carried by said fence, means for adjusting said gauge upwardly and downwardly in relation to the bed plates, said thickness gauge comprising a supporting plate carried by the fence, the movable bed plate being below the elevation of the stationary bed plate, a supporting plate attached to the fence, a vertically adjustable gauge member carried by the supporting plate, the bottom edge of said supporting plate engaging both the stationary and adjustable bed plates, inwardly and upwardly inclined spring fingers carried by the adjustable bed plate, a bolt extending through the outer side of the spring fingers and into the adjustable bed plate, a lug carried by the other side of the spring fingers and disposed in a notch in the lower edge of the supporting plate carried by the fence.

WALTER RAMM.
